UNITED STATES PATENT OFFICE.

WALTER H. ALLEN, OF SENECA FALLS, NEW YORK.

DESIGN FOR A PAPER-WEIGHT.

SPECIFICATION forming part of Design No. 20,716, dated May 12, 1891.

Application filed January 26, 1891. Serial No. 379,199. Term of patent 3½ years.

To all whom it may concern:

Be it known that I, WALTER H. ALLEN, of Seneca Falls, in the county of Seneca, in the State of New York, have invented new and useful Improvements in a Design for Paper-Weights, of which the following, taken in connection with the accompanying drawings, is a full, clear, and exact description.

Figure 1 is an isometrical elevation of my design paper-weight. Fig. 2 is a bottom plan view of the base.

The leading features of my design are the circular base having a flat lower face and a rounded upper face and provided on its vertical edge with an annular groove, as shown, a 15 angular vertical shank supporting the globe, and the globe being the representation of the earth's surface.

A is the base, having a circumferential groove 1 in its outer face.

5 5 is a globe, ornamented with a map of the world, and 3 is a circular stem or support between the globe and the base and bent or curved substantially as shown in Fig. 1, so that said globe is supported in a position out 25 of the plane vertical to the base.

What I claim is—

The design for a paper-weight, substantially as herein described and shown.

In witness whereof I have hereunto set my 30 hand this 26th day of December, 1890.

WALTER H. ALLEN.

In presence of—

H. P. DENISON,
C. W. SMITH.
